ELECTRIC LIGHT BULB WRENCH

Paul S. Daniels, Rocky, Okla.

Application May 19, 1952, Serial No. 288,664

8 Claims. (Cl. 294—20)

1

My invention relates to bulb wrenches, that is devices used in changing electric light bulbs.

One object of my invention is to provide an improved bulb wrench which is simple and rugged and which may be made cheaply.

Another object is to provide a bulb wrench which may be used to remove or replace bulbs of various sizes without adjustment.

Another object is to provide a bulb wrench which will grasp a bulb resiliently both in compression and in torsion.

For a more complete understanding of the nature and scope of my invention reference may be had to the description and drawings in which;

Figure 1 is a view in elevation, partly broken away and in section, of an embodiment of my invention, illustrating how it will engage bulbs of large and small sizes;

Figure 2 is a section taken on line 2—2 of Figure 1; and

Figure 3 is an exploded view of the principal parts of the device shown in Figure 1.

Throughout the description and the figures of the drawing like reference numerals refer to similar parts.

Referring to the drawing, one embodiment of my invention is shown, comprising a pole 1 on the end 1d of which there is mounted a resilient cap 2 through the end 3 of which extend a plurality of elongated bulb gripping elements 4 the lower ends of which are enclosed by the skirt 5 of cap 2.

Bulb gripping elements 4 are preferably of elongated U shape, each having a bight portion 6 which is adapted to engage an electric light bulb 7 or 7a, and depending legs 8 having lower portions 9 and lower ends 10 as best shown in Figure 3. Preferably these U-shaped bulb gripping elements 4 are shaped so that lower portions 9 are closer together than opposing sides of bight portions 6, so as to be better adapted to engage a bulb.

As illustrated in Figure 3, spaced holes 3a are formed in the end 3 of cap 2. These holes are shaped so as to fit legs 8 snugly, and are spaced from the axis of the pole with their centers slightly farther from the axis of the pole than are the centers of ends 10 in the assembled condition. When assembled as illustrated in Figure 1, bulb gripping elements 4 have their lower ends 10 secured to pole 1 while their upper portions project through end 3 of resilient cap 2 and outwardly beyond the end of the pole. Resilient cap 2 resiliently holds legs 8 in proper position and biases bulb gripping elements 4 toward a closed position.

2

Each bulb gripping element 4 is preferably made of a single length of relatively stiff wire 11. Extending approximately at right angles from the lower ends 10 of legs 8 are short extensions 12. Wire 11 is preferably covered from end to end, that is between ends 10—10 but not on extensions 12—12, by a resilient cover 13 which may be of soft rubber.

Spaced around the end of pole 1 there may be 10 a plurality of grooves 14 extending longitudinally and parallel to the axis of the pole 1 which are adapted to accommodate the lower portions 9 of the bulb gripping elements 4, so that when assembled as illustrated in Figure 1 lower ends 9 of the 15 legs 8 lie in the respective grooves 14. Small holes 15 may be provided in the pole perpendicular to its axis adjacent the lower ends of grooves 14. These holes before assembly are preferably slightly smaller in diameter than the diameter 20 of wire 11.

To assemble the device the lower ends 9 of bulb gripping elements 4 are first pushed through holes 3a of cap 2 until extensions 12 protrude below the bottom of the skirt 5. This subassembly is then 25 pushed over the end of pole 1 so that extensions 12 rest over the holes 15. Extensions 12 are then forced into holes 15 by pressing in on ends 10. Cap 2 is then pressed down until it is seated on the end of pole 1, with skirt 5 overlying ends 10, and lower ends 9 lying in grooves 14.

Although not essential, I prefer to provide a ferrule 16 that will surround ends 10 and hold them firmly against the pole. In assembly, the ferrule 16 is first pushed down over the end of 35 the pole below the lower ends of grooves 14. The subassembly of gripping elements and cap is next pushed over the end of the pole and the extensions 12 forced into their holes; the ferrule is then pushed up over ends 10; and cap 2, which 40 may be slightly recessed to accommodate ferrule 16, is finally pressed down into place. As shown in Figure 2, grooves 14 are preferably broader than, but not as deep as, the diameter of resilient cover 13, which is compressed under ferrule 16 45 into the cross-sectional shape 13a.

In lieu of securing ends 10 to the pole by means of extensions 12 embedded in the pole, various other means may be employed. For example, when a wire such as 11 is used, extensions, in the 50 shape of eyes (not shown) may be formed at ends 10 in place of extensions 12, and these may be secured to the pole by screws. When a ferrule or the equivalent, such as 16 is used to bind the ends 10 to the pole extensions 12 or other additional means of securing the ends 10 to the pole

are not essential, the ferrule being sufficient to secure ends 10 to pole 1.

Ferrule 16 may be placed higher on the pole than indicated on the drawing, but to obtain the maximum resiliency of bulb gripping contact and the widest range of bulb size I prefer to place the ferrule over ends 10 as shown.

Bulb gripping elements 4 need not be of the U-shaped form shown in the drawing, but may be elongated elements of any form suitable for engaging a bulb.

While it is essential that bulb gripping elements 4 extend through suitable holes in a resilient cap 2, it is not essential that cap 2 have a skirt portion 5, provided that lower ends 10 are secured to pole 1. That is to say, a cap comprising simply a disc similar to end 3 and having holes 3a therethrough would serve the purpose and be the equivalent of cap 2.

Pole 1 may be made in sections such as 1a and 1b, joined by suitable fittings 1c.

It will be apparent that the resilient cap 3, combined with the method of attaching the bulb gripping elements 4 to the pole 1 at their bottom ends gives a very resilient type of bulb wrench which will accommodate a wide size range of bulbs and engage them firmly yet resiliently both in gripping action and in torsion when screwing and unscrewing them. The wrench is further improved in these respects by covering the bulb gripping elements 4 with resilient covers and by using grooves 14 which are slightly wider than the diameter of the covered bulb gripping elements.

It is believed that the operation will be obvious from the above description. The bulb wrench is simply pushed over the end of a bulb so that the gripping elements 4 resiliently engage it, and the pole 1 twisted in the desired direction, for screwing or unscrewing.

It will be obvious that various modifications of the described embodiments of my invention are possible within the scope of the following claims.

I claim as my invention:

1. A bulb wrench comprising, in combination, a pole, a resilient cap having a top portion and an integrally formed depending skirt portion mounted on the end of said pole, said depending skirt portion embracing the end of said pole, and a plurality of elongated bulb gripping elements having their lower ends secured to said pole and their lower portions extending through said cap, while their upper portions project outwardly beyond the end of said pole, said bulb gripping elements being resiliently biased toward a closed position by said resilient cap, whereby the upper portions of said bulb gripping elements are adapted to flexibly grasp a bulb when engaged therewith to remove or replace the same.

2. A bulb wrench comprising, in combination, a pole, a resilient cap mounted on the end of said pole and having a skirt portion embracing the end thereof, and a plurality of elongated bulb gripping elements having their lower portions extending approximately parallel to each other and to the axis of said pole, while their upper portions project beyond the end of said pole and diverge outwardly from each other, said lower portions extending through the end of said resilient cap and being embraced by the skirt portion thereof, the lower ends of said bulb gripping elements being secured to said pole, and said bulb gripping elements being resilient-

ly biased toward a closed position by said resilient cap, whereby the upper portions of said gripping elements are adapted to flexibly grasp a bulb when engaged therewith to remove or replace the same.

3. A bulb wrench comprising, in combination, a pole, a resilient cap having a top portion and an integrally formed depending skirt portion mounted on the end of said pole, said depending skirt portion embracing the end of said pole, a plurality of elongated bulb gripping elements projecting beyond the end of said pole and having portions extending through said cap, and a ferrule around said pole embracing the lower ends of said gripping elements for engagement with said pole, said bulb gripping elements being resiliently biased toward a closed position by said resilient cap, whereby said elongated bulb gripping elements are adapted to flexibly engage a bulb for removing or replacing the same.

4. A bulb wrench comprising, in combination, a pole, a resilient cap having a top portion and an integrally formed depending skirt portion mounted on the end of said pole, said depending skirt portion embracing the end of said pole, and a plurality of U-shaped gripping loops each having a bight portion and depending legs, said depending legs of said gripping loops extending through said cap and having their ends secured to said pole and said gripping loops being resiliently biased toward a closed position by said resilient cap, whereby the bights of said loops are adapted to flexibly embrace a bulb when engaged therewith for removing or replacing the same.

5. A bulb wrench comprising, in combination, a pole having a plurality of short longitudinal grooves spaced around the end thereof, a resilient cap mounted on the end of said pole and having a skirt portion embracing the end of said pole, and a plurality of U-shaped gripping loops each having a bight portion and depending legs, the lower portions of which legs extend through said resilient cap and lie in said grooves, the ends of said legs being secured to said pole and said gripping loops being resiliently biased toward a closed position by said resilient cap, whereby the bight portions of said gripping loops are adapted to flexibly grasp a bulb when engaged therewith for removing or replacing the same.

6. A bulb wrench comprising, in combination, a pole having a plurality of short longitudinal grooves spaced around the end thereof, a resilient cap mounted on the end of said pole and having a skirt portion embracing the end of said pole, and a plurality of U-shaped wire gripping loops each having a bight portion and depending legs, said legs having extremities extending from their lower ends approximately at right angles to said legs, the wires of said gripping loops being covered with resilient covers except on said extremities, the lower portions of said legs with their resilient covers extending through said resilient cap and lying in said grooves, said extremities being embedded in said pole and said gripping loops being resiliently biased toward a closed position by said resilient cap, whereby the said bight portions of said gripping loops are adapted to flexibly grasp a bulb when engaged therewith for removing or replacing the same.

7. A bulb wrench comprising, in combination, a pole having a plurality of short longitudinal grooves spaced around the end thereof, a resilient cap mounted on the end of said pole and having

5

a skirt portion embracing the end of said pole, a plurality of U-shaped wire gripping loops each having a bight portion and depending legs and a resilient cover on said wire, the lower portions of said legs with their resilient cover extending through said resilient cap and lying in said grooves, a ferrule around the end of said pole embracing the lower ends of said legs for engagement with said pole and said gripping loops being resiliently biased toward a closed position by said resilient cap, whereby the said bulb wrench is adapted to flexibly engage a bulb for removing or replacing the same.

8. A bulb wrench comprising, in combination, a pole, a resilient cap having a top portion and an integrally formed depending skirt portion mounted on the end of said pole, said depending skirt portion embracing the end of said pole, a plurality of U-shaped gripping loops each hav-

6

ing a bight portion and depending legs, and a ferrule surrounding the skirt of said cap over the lower ends of said legs for securing said legs to said pole, said legs extending through said cap and said gripping loops being resiliently biased toward a closed position by said resilient cap, whereby the said bulb wrench is adapted to flexibly engage a bulb for removing or replacing the same.
